CLAIM

The ornamental design for a workstation, as shown and described.

DESCRIPTION

FIG. 1 is a front, first side, top perspective view thereof of a workstation according to my design;

FIG. 2 is a back, second side, bottom perspective view thereof;

FIG. 3 is a front view thereof;

FIG. 4 is a back view thereof;

FIG. 5 is a top view thereof;

FIG. 6 is a bottom view thereof;

FIG. 7 is a first side view thereof; and,

FIG. 8 is a second side view thereof.

The broken lines shown in the drawings are included for the purpose of illustrating environmental structure and form no part of the claimed design.

1 Claim, 7 Drawing Sheets
